P. WIRSCHING.
 TRACKER BAR FOR SELF PLAYING MUSICAL INSTRUMENTS.
 APPLICATION FILED JAN. 3, 1910.

1,074,335.

Patented Sept. 30, 1913.

UNITED STATES PATENT OFFICE.

PHILIPP WIRSCHING, OF SALEM, OHIO, ASSIGNOR TO THE WIRSCHING ORGAN COMPANY, OF SALEM, OHIO, A CORPORATION OF OHIO.

TRACKER-BAR FOR SELF-PLAYING MUSICAL INSTRUMENTS.

1,074,335.

Specification of Letters Patent.

Patented Sept. 30, 1913.

Application filed January 3, 1910. Serial No. 536,021.

To all whom it may concern:

Be it known that I, PHILIPP WIRSCHING, a citizen of the United States, residing at Salem, in the county of Columbiana and 5 State of Ohio, have invented a certain new and useful Improvement in Tracker-Bars for Self-Playing Musical Instruments, of which the following is a full, clear, and exact description, reference being had to the 10 accompanying drawings.

This invention relates generally to self-playing musical instruments, and more particularly to the tracker-bars for such instruments and it has for its object the provision 15 of means for causing the perforated note sheet to lie tightly against the face of the tracker-bar during the operation of the instrument. As is well understood by all persons who have used self-playing instruments 20 in which a perforated sheet of paper is employed, such sheet is affected by weather conditions, the same stretching or shrinking or warping out of shape so that parts of the sheet may not lie closely in contact with the 25 tracker-bar, with the result that the air is drawn or forced beneath the sheet and enters perforations in the tracker-bar which should be closed, thus causing discordant notes to sound. This trouble is especially noticeable 30 in those music-rolls in which long parallel slots are brought close together so that they are separated by merely a narrow strip.

In my invention I employ a hollow tracker-bar, the same being fluid-tight, except at certain perforations on its front face and at one or more perforations on its rear face, the object being to maintain in the tracker-bar a fluid pressure differing from that outside the tracker-bar.

40 In the drawings forming a part of this application, Figure 1 is a transverse sectional view taken through the tracker-bar, the rollers for the note sheet and the air tight casing surrounding said bar and rollers, the device shown in said figure being 45 adapted for the operation of the instrument by wind pressure; Fig. 2 is a front elevation of a portion of the tracker-bar shown in Fig. 1, said figure also showing a part of a perforated sheet; Fig. 3 is a plan view of the 50 tracker-bar shown in Figs. 1 and 2; Fig. 4 is a transverse section through the tracker-bars shown in Figs. 1, 2 and 3; Fig. 5 is a transverse section taken through a tracker- 55 bar that is adapted for operating on the suc-

tion principle; and Fig. 6 is a front elevation of a portion of a tracker-bar of a somewhat modified form.

Taking up a complete description of my invention by the use of reference characters, 60 1 and 2 represent the rolls or spools for the perforated note sheet 3. This sheet is fed over a tracker-bar, the front wall of which is shown at 4, the side or edge walls at 5 and the rear wall at 6. Arranged in a longitudinal row at substantially the center of the front wall 4 are the ordinary orifices 7, with which the perforations 8 in the note sheet are made to coincide as the said sheet is fed. At the rear of each of the orifices 7 I place a 65 metallic tube 9, said tubes being secured to the tracker-bar so as to surround the orifices and form a fluid-tight joint with the front wall. The tubes 9 are preferably arranged in two series, the tubes alternating in the 70 said series, so that substantially half of the tubes extend upwardly at a slight angle and the remaining tubes extend downwardly at a 75 slight angle, as shown in Fig. 4. The tubes 9 pass through the rear wall 6 of the tracker-bar, a fluid-tight joint being formed with said wall in any suitable manner. To the projecting ends of the tubes 9 I attach the rubber tubes 10 that lead to or are connected with the pneumatics. Extending through 80 the front wall 4 of the tracker-bar at one side of the row of orifices 7 is a series of slots 11, and a corresponding series of slots 12 is preferably placed on the opposite side of the said row, as shown in Fig. 2. The 85 slots 11 and 12 are, therefore, preferably arranged in pairs, the slots in each pair lying on opposite sides of the row of orifices 7 and in a line which passes between adjacent orifices so that the slots 11 and 12 are never 90 uncovered by the perforations 8 of the sheet 3. At one or more points in the rear face of the tracker-bar I attach tubes 13, said tubes communicating with the interior of the tracker-bar.

95 In the form of device shown in Fig. 1, the rolls 1 and 2 and the tracker-bar are enclosed within a fluid-tight casing, the same consisting of the stationary top, rear and bottom walls 14, 15, 16 respectively and of the front glass panel 17, said panel being suitably packed so as to provide a fluid-tight casing and yet be capable of sliding so as to permit of access to the rolls. The tubes 10 lead outwardly through the rear of the cas- 100 105 110

ing and form with the rear wall thereof a fluid-tight joint. The tubes 13 of the tracker-bar also communicate with the exterior of the casing through metallic thimbles 18 that project through the rear wall of the casing, the tubes 13 and thimbles 18 being connected by rubber tubes 19. Fluid under pressure may be forced into said casing through a pipe 20 that is connected to 10 suitable bellows.

The operation of the device shown in Fig. 1 is as follows:—Having placed the perforated sheet upon the rolls and closed the front panel 17 of the box, and having started 15 the operation of the bellows, air is forced into the closed casing so that, outside of the tracker-bar and of the tubes 10 and 19, the pressure is raised above that of the atmosphere. As is well understood, when one of 20 the perforations 8 of the sheet 3 coincides with an orifice 7 in the tracker-bar, air is permitted to pass from the casing through the orifice and the pneumatic tube 10 which leads to the corresponding pneumatic. The 25 interior of the tracker-bar outside of the tubes 9 is maintained at atmospheric pressure by connecting such interior with the atmosphere through the tubes 13, 18 and 19. There is, therefore, a difference of pressure 30 maintained between the outside and the inside of the tracker-bar, so that there is always a tendency for the perforated sheet 3 to be blown through the slots 11 and 12. The pressure of the air on the outer face of 35 the sheet holds the latter tightly over said slots and thus maintains the sheet in close contact with the tracker-bar on both sides of the row of orifices 7.

In Fig. 5 I have shown the tracker-bar as 40 it is used on instruments which play by suction rather than by air pressure. In said figure, 4, 5 and 6 represent the front, the edge and the rear walls respectively of the tracker-bar. The tracker-bar is hollow, as 45 in Fig. 1, and through the same passes the metallic tubes 9, with which are connected the rubber tubes 10 that lead to the pneumatics. Through the front wall of the tracker-bar above the center is a series of 50 slots 11, and a corresponding series of slots 12 are also located below the center. Communicating with the interior of the tracker-bar is one or more tubes 19^a, said tubes corresponding to tubes 19 hereinbefore 55 described. Instead of the tubes 19^a leading to the open air, they lead to a suitable suction device 25, a partial vacuum being maintained in said device by any suitable means. In this form the tracker-bar is not confined 60 within an air tight casing, so that the bar is surrounded by air at atmospheric pressure. By connecting the interior of the tracker-bar with the suction device 25, a partial vacuum is maintained within the bar so that 65 the note sheet is held tightly over the slots

11 and 12. This form, therefore, differs from the previous form in that the variation in pressures is secured by exhausting below the atmosphere while in the former case it is maintained by keeping the pressure in the 70 casing above the atmosphere.

In Fig. 6 I have shown a slight modification of the tracker-bar in which small perforations 11^a and 12^a are substituted for the slots 11 and 12. This form of tracker-bar 75 operates in precisely the same manner as the one previously described.

Having thus described my invention what I claim is:

1. In an instrument adapted to be pneumatically controlled by a perforated sheet, a tracker-bar over which said sheet may pass which has a row of playing apertures constantly in the path of the perforation of the sheet, supplemental openings on each side of the row of playing apertures and midway between the paths of the perforations of the note sheet, individual tubular connections to each playing aperture, a connection common to the supplemental apertures, and means 80 for creating a preponderance of atmospheric pressure on the working face of the tracker bar whereby the note sheet is held to the tracker-bar by air pressure against the portions of the note sheet covering the supplemental openings. 90

2. A tracker bar for an instrument of the character described comprising a hollow member with a front wall having through it a row of apertures and another row of apertures out of longitudinal alinement with reference to the first row, each aperture of the second row having its center on a line passing through the center of the space between the apertures of the first row at right 100 angles to the row, and means for creating a preponderance of atmospheric pressure on the working face of the tracker bar whereby a note sheet having its perforations registering with the apertures of the first row is 105 held to the tracker-bar by air pressure, the tracker bar being air tight except for the second row of apertures and an exit opening. 110

3. A tracker bar for an instrument of the character described comprising a hollow 115 member with a front wall having through it a row of apertures, tubular connections to each aperture extending outside the hollow member, an auxiliary row of apertures on each side of the first row, each aperture of 120 the auxiliary rows having its center on a line at right angles to the first row and passing through the center of the space between the apertures of said row, and means for creating a preponderance of atmospheric pressure 125 on the working face of the tracker bar whereby a note sheet having its perforations registering with the apertures of the first row is held to the tracker bar by air pressure, the tracker bar being air tight except 130

for the auxiliary apertures and an exit opening.

4. A tracker bar for an instrument of the character described comprising a hollow member with one wall having through it a row of playing apertures, tubular connections to each of said apertures extending outside the hollow member, supplemental apertures above and below the playing apertures, each of these apertures being centrally located on a line at right angles to the row of playing apertures and passing midway through the space between said apertures, an opening from the tracker-bar, said

tracker bar being air-tight except for the 15 supplemental apertures and said opening, and means for creating a preponderance of atmospheric pressure on the working face of the tracker bar whereby a note sheet having its perforations registering with the 20 playing apertures is held to the tracker bar by air pressure.

In testimony whereof, I hereunto affix my signature in the presence of two witnesses.

PHILIPP WIRSCHING.
